UNITED STATES PATENT OFFICE

154,779

DESIGN FOR AN EXPANSIBLE CHAIN FOR A BRACELET OR SIMILAR ARTICLE

George A. Ingleby, Cranston, R. I., assignor to The
Hadley Company, Incorporated, Providence,
R. I., a corporation of Rhode Island

Application April 1, 1949, Serial No. 1,762

Term of patent 7 years

(Cl. D45—4)

To all whom it may concern:

Be it known that I, George A. Ingleby, a citizen of the United States of America, residing in Cranston, county of Providence, and State of Rhode Island, have invented a new, original, and ornamental Design for an Expansible Chain for a Bracelet or Similar Article, of which the following is a specification, reference being had to the accompanying drawing, forming a part thereof.

Fig. 1 is a top plan view of an expansible chain, embodying my new design with the links in a contracted position;

Fig. 2 is a similar view to Fig. 1 with the links in an expanded position, portions of the conventional appearing button links being visible between the expanded links;

Fig. 3 is a top view of a single one of the top links of the bracelet; and

Fig. 4 is an edge elevational view of one of the top links.

I claim:

The ornamental design for an expansible chain for a bracelet or similar article, as shown.

GEORGE A. INGLEBY.
